UNITED STATES PATENT OFFICE.

JAMES W. JENNINGS, OF PROVIDENCE, RHODE ISLAND, ASSIGNOR TO QUAKER SILVER COMPANY, OF ATTLEBORO, MASSACHUSETTS, A CORPORATION OF MASSACHUSETTS.

DESIGN FOR A SALT OR PEPPER SHAKER OR SIMILAR ARTICLE.

Application filed November 17, 1928. Serial No. 28,931. Term of patent 7 years.

To all whom it may concern:

Be it known that I, JAMES W. JENNINGS, a citizen of the United States of America, residing at 169 Calla Street, in the city of Providence, county of Providence, and State of Rhode Island, have invented a new, original, and ornamental Design for Salt or Pepper Shakers or Similar Articles, of which the following is a specification, reference being had to the accompanying drawing, forming a part thereof.

In said drawing:

Fig. 1 is a front elevation of a salt or pep-

per shaker or similar article showing my new design; and

Fig. 2 is a sectional view on the line 2—2 of Fig. 1.

I claim:

The ornamental design for a salt or pepper shaker or similar article substantially as shown.

Signed by me at Attleboro, in the county of Bristol and Commonwealth of Massachusetts, this 8th day of November, 1928.

JAMES W. JENNINGS.
